(57) **CLAIM**

The ornamental design for a robot, as shown and described.

DESCRIPTION

FIG. 1 is a front perspective view of a robot illustrating our new design;

FIG. 2 is a front view thereof;

FIG. 3 is a back view thereof;

FIG. 4 is a right side view thereof;

FIG. 5 is a left side view thereof;

FIG. 6 is a top side view thereof;

FIG. 7 is a bottom side view thereof;

FIG. 8 is a front perspective view of a robot illustrating a second embodiment of our new design;

FIG. 9 is a front view thereof;

FIG. 10 is a back view thereof;

FIG. 11 is a right side view thereof;

FIG. 12 is a left side view thereof;

FIG. 13 is a top side view thereof; and,

FIG. 14 is a bottom side view thereof.

The broken lines shown in the drawings depict portions of the robot that form no part of the claimed design.

1 Claim, 14 Drawing Sheets
